UNITED STATES PATENT OFFICE.

EDWARD DEWALD, SR., OF CINCINNATI, OHIO, ASSIGNOR OF ONE-HALF TO EDWARD DEWALD, JR., OF CINCINNATI, OHIO.

SWIVEL-PLUG CONNECTOR.

Application filed March 8, 1920. Serial No. 364,315.

To all whom it may concern:

Be it known that I, EDWARD DEWALD, Sr., a citizen of the United States, residing in Cincinnati, in the county of Hamilton and 5 State of Ohio, have invented new and useful Improvements in a Swivel-Plug Connector, of which the following is a specification.

An object of my invention is to produce a swivel plug connector of the general type 10 disclosed in my Patent Number 1,316,561 and in my copending application serially numbered 347,365, in which much greater compactness of construction is attained than in either of the previous constructions 15 and in which greatly increased ease and efficiency of operation is also attained.

This and other objects are attained in the swivel plug described in the following specification and illustrated in the accompanying 20 drawings in which:—

Fig. 1 is an elevational section of my improved connector, upon an enlarged scale.

Fig. 2 is a transverse section upon the line 2—2 of Fig. 1.

25 Fig. 3 is a view of a detail of my invention.

Fig. 4 is a transverse section upon the line 4—4 of Fig. 1.

Fig. 5 is a view of a detail of my invention.

Fig. 6 is an elevational section of my improved connector, upon an enlarged scale, but showing a somewhat modified form thereof.

35 Fig. 7 is a transverse section upon the line 7—7 of Fig. 6.

Fig. 8 is a transverse section upon the line 8—8 of Fig. 6.

40 Fig. 9 is a transverse section upon the line 9—9 of Fig. 6.

In my improved construction a body 9 encloses the principal elements of the connector, a cap 10 being provided at one end of the body for carrying a screw ferrule 11 of metal 45 adapted to enter the usual screw socket of electrical fittings. At the opposite end of the body a cap 12 is provided for holding the electric cable 13 leading from the connector, a clamping nut 14 being screwed upon a split extension 15 of cap 12 for clamping cable 13 tightly. Body 9 and caps 10 and 12 are of insulating material and extending through the body is a spindle 16 also of insulating material. The lower end 17 of 55 spindle 16 is enlarged and screw threaded

for carrying cap 12 and a lock nut 18 which is also of insulating material.

Upon spindle 16 are two metal collars 20 and 21 which are separated by an insulating washer 22 and the collars are provided with the respective outwardly extending annular flanges 23 and 24. Against the under faces of these collars the respective sets of metal balls 25 and 26 bear, the former being located in a metal race 27 and the latter being 60 located in a metal race 28, race 27 bearing upon a shoulder 9^a of the body 9 and having beneath it a metal washer 29 which is held to collar 20 by a screw 30 which also passes into spindle 16, and race 28 bearing upon a 65 metal washer 31 which is held to collar 21 by a screw 32 which also passes into spindle 16. Beneath collar 20 and washer 29 an insulating washer 19 is located. Washer 19 has two lugs 35, see Fig. 5, which bear against elements 38 and 43 which are hereinafter described, to hold these elements in position and particularly to hold element 43 from contact with collar 20. Washer 22 cooperates with washer 19 in a similar manner by 70 having a lug 47, see Fig. 3, which bears against elements 43.

Race 27 is connected to cap 10 and screw ferrule 11 by a metal strip extension 33 which extends through the cap and after being bent 75 over is soldered as shown at 34 in Fig. 1, to ferrule 11. Extending from race 28 a metal strip 36 passes through cap 10 and is bent over and screwed to the top of the cap as shown at 37 to form the opposite terminal 80 contact.

To connect cable 13 to the plug terminals 34 and 37, a strip of metal 38 to which collar 23 is attached by means of screw 30, extends along spindle 16, through the enlarged end 85 17 thereof into slot 39 where a screw 40 connects one wire 41 of cable 13 thereto. To connect the opposite wire 42 of cable 13 to collar 21, a metal strip 43 extends from connecting screw 32 of collar 21 along spindle 16, through the enlarged end thereof into a slot 44 where a screw 45 connects the opposite wire 42 of the cable 13 to strip 43.

In Figs. 6 to 9 inclusive the connector shown in Figs. 1 to 5 inclusive has been 105 adapted to connecting two cables instead of a screw socket and a cable. The cap 10 and screw ferrule 11 have been removed from the construction as shown in Fig. 1 and in lieu thereof a disc 48 and cap 49, both of 110

insulating material, have been substituted and these elements are preferably held in place by screws 50. A split screw threaded extension 51 of cap 49 is provided with a 5 clamping nut 52 which performs the same function as nut 14 of the lower end of the connector in clamping cable 53 tightly. Molded or otherwise located in disc 48 are nuts 54 which receive screws 55 which pass 10 through the bent over ends 56 of the strips 33 and 36 and around which wires 57 and 58 of the cable 53 are placed. The remaining parts of the connector are the same below the disc 48 as in the previously described 15 screw plug type and bear the same reference numerals, hence repeated description of this portion of the construction is thought unnecessary.

It is thought that the operation of the 20 connector is sufficiently self evident from the construction which has been described, as to need no further explanation, the drawings clearly showing the operation.

Having thus described my invention what 25 I claim is:—

In a swivel plug connector, a body, a spindle within the body, a ball race within

the body for the positive pole and a ball race within the body for the negative pole of a 30 source of current supply, each of said races having a ball contacting surface to support the bottom surfaces of balls located therein, a ball race on the spindle for each ball race in the body, each of said races having a surface to contact the top surfaces of balls located therein, balls within the races establishing electrical connection between the races for the positive and between the races for the negative poles of current supply, 35 electrical conductors attached to and extending from the body ball races through the body to one end thereof, electrical conductors attached to and extending from the spindle ball races through the spindle to one end thereof away from the body conductors, and means at the body end and at the spindle end of the connector adapted to 40 connect wires thereto.

In witness whereof, I affix my signature in the presence of two witnesses.

EDWARD DEWALD, Sr.
